UNITED STATES PATENT OFFICE.

VALENTIN WEX, OF MUNICH, GERMANY.

CURLING OR CRIMPING TONGS.

No. 888,861.

Specification of Letters Patent.

Patented May 26, 1908.

Application filed February 26, 1907. Serial No. 359,459.

To all whom it may concern:

Be it known that I, VALENTIN WEX, citizen of Germany, residing at Munich, Bavaria, Germany, have invented certain new and useful Improvements in Curling or Crimping Tongs; and I do hereby declare the following to be a full, clear, and exact description of the invention, such as will enable others skilled in the art to which it appertains to make and use the same.

Tongs for curling or waving hair in which the one part or member of the tongs is provided with several slidingly arranged bars with rib-like, curved teeth and the other part 15 of the tongs is bifurcated in such a manner that on closing the tongs the blades or prongs of the fork will lie on either side of the bars are already known.

In order to form the so-called Marcel waves with such tongs, it is necessary to use one hand or a hand comb to hold the hair at the side during the forward movement of the toothed bars. It is well known that to form the Marcel waves the hair must be undulated or waved in two directions at right angles to each other, the ridges of the waves as seen from the side of a strand of hair appearing almost pointed. In order then to be able to form such Marcel waves with curling tongs 20 of the kind described above, without using a hand comb or the like, combs are arranged parallel to the bars on the outer sides of the part of the tongs carrying these bars. Between these combs and the neighboring bars 25 the corresponding prongs or blades of the other untoothed lever of the tongs lie when the latter is closed.

It is indeed already known that fixed side combs may be arranged on curling tongs 30 with longitudinally movable toothed bars. But in the case of the heretofore known curling tongs the longitudinally movable toothed bars and fixed side combs are not on the same part or member of the tongs. Moreover, the heretofore known tongs did not permit of the toothed bars being shifted by the same hand that held the tongs. By arranging the fixed side combs on that lever of the tongs which carries the longitudinally movable toothed bars, the tongs being arranged 35 for manipulation with one hand alone, the formation of these Marcel waves is so greatly simplified that any person without special practice in the art can forthwith wave hair with one hand.

The accompanying drawings show in Fig-

ures 1 to 5 one form of construction of such a pair of curling tongs, Figs. 6 to 10 illustrating a second form of construction. Fig. 1 is a side view, Fig. 2 a plan view, and Fig. 4 a 60 sectional view of the closed tongs according to the first constructive form; Fig. 3 is a side view of the same when open, and Fig. 5 a plan view of the one half *e* of the tongs. In Fig. 6 is shown a side elevation of a modified 65 form of tongs embodying my invention; Fig. 7 a plan view thereof; Fig. 8 a cross section of the same; Fig. 9 a side elevation of the said tongs in open position; and Fig. 10 a bottom view of the same closed.

According to these drawings the member *e* of the tongs is provided in both forms of construction on either side with a fixed comb *a*. These combs *a* constitute the device for holding the hair. Between the combs *a* the 75 slides or bars *b* are longitudinally movably arranged on the guide rods *c*, which slides *b* may be connected with and shifted longitudinally by any suitable mechanism. The bars *b* are provided at certain proper intervals with projections in the form of ribs or teeth *n* extending nearly across the whole width of the bars and of which the operative surfaces receive a curve corresponding to the curve of the hair wave it is desired to form. 80

In the drawings these ribs or teeth *n* have a bow-like form, so that viewed from above, as seen in Figs. 2, 5 and 7, they appear lozenge shaped. In this form of my device, as well as the modification presented in Figs. 90 6 to 10, it will be noted that the means or mechanism for shifting or moving the slides *b* longitudinally are mounted on one or the other of the two pivoted members *e*, *m*, of the tongs.

According to the first form of construction (Figs. 1 to 5) the mechanism for moving the slides *b* consists of a lever *d* pivotally secured to the handle of the part or member *e* of the tongs and jointed to the arm *g* which latter 100 is rigidly secured to the middle bar *b*. A lever *h* rigidly mounted on the axle *i* and pivoted in lateral bearing pieces of the member *e* engages in a slot of the arm *g*. On the axle *i* are further secured the crank arms *k* 105 connected by means of links *l* with the two outer slides *b*. The other member *m* of the tongs is provided with a grooved or fluted cover *f* (see in particular Fig. 4) arranged to incase the teeth *n* of the slides *b* when the 110 tongs are closed the adjoining edges of these grooves forming ribs or blades which extend

between the slides *b* and between the combs *a* and the bars *b*.

In the second form of construction the mechanism for moving the bars consists of a lever or handle *d* rigidly secured to one arm of a two-armed lever *o* pivotally secured to the part *e* at *p*. The ends of this lever *o* are linked to the sliding pieces *q* which are attached to the inner sides of the slides or bars *b*, so that when the handle *d* is pushed to one side, as shown by the dotted lines in Fig. 10, the slides or bars *b* will be longitudinally shifted in opposing directions, the sliding pieces *r* serving as guides.

The manipulation of the first described pair of tongs (Figs. 1 to 5) is as follows: After the tongs have been heated the strand of hair to be curled is laid between the two members of the tongs and the tongs again closed. The hair now lies in the combs *a* and on the slides *b* and is so influenced by the prongs or blades of the member *m* that it adapts itself to the curved surfaces of the slides *b*. If now the lever *d* is pressed, the above-described connections will cause the middle slide *b* to move forward and the two side bars backward, the teeth *n* of the slides *b* engaging with the hair and forcing it to partake of the motion of the slides *b*; at the same time the hair is held on either side by the combs *a*.

In the second form of construction (Figs. 6 to 10) a sideward movement of the lever *d* causes the slides *b* to be shifted longitudinally in opposing directions, the teeth *n* again forcing the hair which is held at the sides by the combs *a* to partake of this motion.

What I claim as new, and desire to secure by Letters Patent, is:—

1. In curling or crimping tongs, a member provided with outer longitudinal combs and a slide arranged between the combs carrying

projections, in combination with a second member pivoted thereto having longitudinal blades extending between the slide and the combs, and means mounted on one of the members for shifting the slide longitudinally.

2. In curling or crimping tongs, a member provided with outer longitudinal combs and slides arranged between said combs and carrying projections, in combination with a second member pivoted thereto having blades extending between the slides and between the slides and the combs, and means mounted on one of the members for shifting the slides longitudinally in opposite directions with relation to each other.

3. In curling or crimping tongs, a member provided with outer longitudinal combs and a slide arranged between the combs and formed with projections, in combination with a second member pivoted thereto having longitudinal blades extending between the slide and the combs and a cover to extend over the slide, and means for shifting the slide longitudinally.

4. In curling or crimping tongs, a member provided with outer longitudinal combs and slides arranged between said combs and formed with projections, in combination, with a second member pivoted thereto and having blades, a grooved or fluted cover extending between the slides and between the slides and the combs, and means for shifting the slides longitudinally in opposite directions with relation to each other.

In testimony whereof I hereunto affix my signature in the presence of two witnesses.

VALENTIN WEX.
